UNITED STATES PATENT OFFICE.

JAMES H. GIDEON, OF CAVOUR, SOUTH DAKOTA.

STEEL TIE.

1,228,903.

Specification of Letters Patent.

Patented June 5, 1917.

Application filed June 30, 1915. Serial No. 37,302.

To all whom it may concern:

Be it known that I, JAMES H. GIDEON, a citizen of the United States, residing at Cavour, in the county of Beadle, State of 5 South Dakota, have invented certain new and useful Improvements in Steel Ties; and I do hereby declare the following to be a full, clear, and exact description of the invention, such as will enable others 10 skilled in the art to which it appertains to make and use the same.

The present invention is directed to metallic railway ties, and has for its object to provide a tie of this nature which is hollow 15 throughout its length.

A further object of the invention is to provide a hollow railway tie of this type so constructed that snow and dirt will be prevented from entering the interior of the tie. 20 A still further object of the invention is to provide a novel means for securing the rails to the tie.

With these and other objects in view this invention resides in the novel features of 25 construction, formation, combination and arrangement of parts to be hereinafter more fully described, claimed and illustrated in the accompanying drawing, in which:

30 Figure 1 is a side elevation of the tie.
Fig. 2 is a longitudinal vertical sectional view through the same.

Fig. 3 is an end view.

35 Fig. 4 is a sectional view on line 4-4 of Fig. 1.

Referring to the drawing 1 indicates the tie, which is formed from sheet metal, and is hollow throughout its length, as clearly shown in Fig. 2 of the drawing.

40 Fixed to one side of the tie is a plate 2 which has its outer end formed with sleeves 3, said sleeves being spaced apart so that the sleeve 4 carried by the closure plate 5 may engage therebetween. The sleeves 3 and 4, when in registry are adapted to receive the pintle bolt 6, whereby the closure plate is hinged to the plate 2.

Upon the opposite side of the tie 1 is fixed a spring latch 7 which is adapted to engage the free end of the plate 5 so as to 50 hold the same in its closed position, thereby closing the ends of the tie so that dirt and snow cannot enter the interior of the tie.

It will be of course understood that each 55 end of the tie is provided with a closure plate.

The tie has its top provided with threaded openings 8 which are engaged by the bolts 9, said bolts being passed through the 60 clamping jaws 10. The clamping jaws 10 have their inner ends engaged with the base flanges of the rails 11, thereby firmly holding the rails in place upon the tie.

It is a well known fact that dirt and 65 snow enter the usual hollow metallic tie, which tends to rust the tie, thus shortening the life of the same, whereas a tie equipped with the closure plates herein described will exclude dirt and snow, and as well rain 70 water.

What is claimed is:—

In combination with a hollow railway tie having open ends, a plate connected to one of the sides of the tie at each end 75 thereof and having a portion thereof bent around the end of the tie and provided with vertically spaced bearing sleeves, a closure plate for each end of the tie having one of its vertical edges provided with a 80 bearing sleeve adapted to align with the first mentioned sleeves, a pintle engaging in said sleeves for hingedly connecting said closure plate to the first named plate, and resilient latches carried by the other side of 85 the tie and yieldably engaging the free ends of the closure plates.

In testimony whereof, I affix my signature, in the presence of two witnesses.

JAMES H. GIDEON.
